CABLE STRIPPER OR SIMILAR ARTICLE

Richard M. Peters, Cloquet, Minn., assignor to Dix, Inc.,
Cloquet, Minn., a corporation of Minnesota

Filed Aug. 3, 1961, Ser. No. 66,237

Term of patent 14 years

(Cl. D22—3)

FIG. 1

FIG. 2

FIG. 3

FIG. 4

FIG. 5

FIG. 1 is a side elevational view of a cable stripper or similar article, embodying my new design;

FIG. 2 is a top plan view;

FIG. 3 is a bottom plan view;

FIG. 4 is a front end elevational view on an enlarged scale; and

FIG. 5 is a cross sectional view on an enlarged scale taken along the line 5—5 of FIG. 1.

The side not shown is the same in appearance as the side shown.

The dominant features of my design reside in the portions shown in full lines and consist in the shape and configuration of the flat portion located at the curved

end of the blade and which extends from the proximal tip of the curved end portion of the blade completely to the distal edge of the curved end portion of the blade, all as shown.

I claim:

The ornamental design for a cable stripper or similar article, as shown and described.
